INDEX CARD

Filed June 13, 1928

UNITED STATES PATENT OFFICE.

GEORGE H. DAWSON, OF BOSTON, MASSACHUSETTS, ASSIGNOR TO SERVICE BUREAU, INC., OF CAMBRIDGE, MASSACHUSETTS, A CORPORATION OF MASSACHUSETTS.

INDEX CARD.

Application filed June 13, 1928. Serial No. 284,994.

This invention relates to index cards for vertical filing systems and particularly to improvements in the projecting tab and transparent label holder of a guide card 5 which is customarily employed in the usual vertical file to separate into identified groups the cards, folders or other subject matter constituting the filing system.

The principal object of the invention is to 10 provide a transversely curved tab at the upper margin of the guide card and a cooperating and correspondingly curved transparent label holder or sheath applied over the tab in such manner that an index slip 15 or label may be readily inserted between the card tab and its protecting sheath and will be frictionally retained in its desired position without the necessity of providing abutments or other means for positioning 20 and securing the label. Further objects reside in the particular construction of the elements hereinafter described and pointed out in the appended claims, which furnish a guide tab of simple and economical construction, possessing great strength, rigidity and 25 resistance to distortion during handling.

Recommended embodiments of the invention are shown for the purpose of illustration in the accompanying drawings, in 30 which:

Fig. 1 is a face view of a portion of an index card equipped with the improved tab and protective sheath;

Fig. 2 is a rear view of the device of 35 Fig. 1;

Fig. 3 is an enlarged section on the line 3—3 of Fig. 1 with portions beyond the plane of section omitted; and

Figs. 4, 5 and 6 are views corresponding 40 to Figs. 1, 2 and 3, respectively, illustrating a modification.

The guide card may be made of any suitably stiff sheet material such as cardboard, fiber board or heavy paper, and comprises a 45 body portion 7 and an integral projecting tab or tongue 8 at its upper edge, which is usually narrower than the body portion and which serves as a convenient handle for tilting or raising the guide and as a carrier for 50 upstanding signals adapted to identify the file contents located behind the guide. As the tab is normally subjected to considerable manipulation, particularly when employed in a vertical visible system in which card 55 groups are raised or "fanned out" by lift-

ing the guide card, it is necessary to provide an encasement or protective sheath to stiffen the tab and to resist the tendency of the tab to crack or break under handling stress. Both metal and celluloid protectors have 60 heretofore been employed for this purpose; but the former are expensive to manufacture and the latter have not afforded the requisite 65 rigidity and durability when applied, as heretofore, as a flat-sided sheath upon a straight, plane card tab.

Accordingly the tabs of the present improvement are transversely curved as indicated in Figs. 3 and 6 and pressed in the desired shape to form permanent corrugations or arches substantially parallel to the upper edge of the card body. In Fig. 3, the tab 8 is curved forwardly and then rearwardly of the plane of the body portion 7; whereas in Fig. 6, the tab is curved only in 75 one direction, rearwardly of the plane of the body.

The transparent protective sheath or label holder, preferably consisting of a strip of sheet celluloid, is adapted to encompass the 80 tab 8 and is curved or corrugated to correspond with the formation of the tab to which it is applied. The sheath is folded over the top of the tab to provide a front flap 9 and a rear flap 10, and the lower corners 85 of the respective flaps are preferably secured to the card body by suitable fastenings, such as the rivets or eyelets 11. Additional intermediate eyelets 12 (Figs. 1 to 3) may be used to secure the bottom of the rear flap if 90 desired.

The side edges of the sheath flaps preferably register with the sides or shoulders of the tab 8 and the rear flap 10 is preferably held close against the rear surface of the 95 card and its tab. Accordingly the flap 10 may be cemented or otherwise united to the tab, thus dispensing with other fastenings. The front flap 9, however, is preferably secured at its lower corners as shown, so as to 100 permit the insertion of a removable paper label or index slip 13 between it and the front face of the tab 8, whereby the label will be frictionally retained within the sheath holder, by reason of the corrugated 105 formation of the tab and sheath, against casual displacement in a vertical direction. Accordingly, the label is preferably inserted from the bottom of the flap 9 (as best indicated in Fig. 4), and the bottom edge of 110

the flap is cut away intermediate its corners, as on the curve 14, to permit the label to be readily removed by grasping its lower margin. The bottom edge of the rear flap 5 may curve downwardly as at 15, or may be otherwise formed so as to avoid registration with the edge 14 along a line upon which the card might tend to bend.

The lower margins of the front flap 9 10 preferably overlap the bottom corners of the label 13 when the latter is fully inserted, and the corner fastenings 11 are preferably so disposed as to prevent sidewise displacement of the label, as shown in Fig. 1. Any 15 desired form of signal or index character may be displayed by printing or otherwise upon the face of the label, and for some purposes of this invention the identifying symbols may be inscribed directly upon the card 20 tab 8. In either case the signals are so displayed as to be readily visible through the curved front flap of the transparent sheath, and are completely protected from moisture or soiling by said flap.

25 The device illustrated in Figs. 4 to 6 shows a modified type of label as well as an optional form of the protected tab. In these views the labels 16 are prepared in strip form and are connected to each other 30 at the transverse perforations or weakened lines 17, so that the end label may be inserted beneath the flap 9 and separated by tearing along the perforations when it is partially inserted, as indicated in Fig. 4. 35 The label may then be pushed upwardly until its top edge substantially abuts the fold line of the sheath and its lower corners are covered by the front flap as in Fig. 1.

An index tab constructed as above recommended is simple and economical to manufacture, and durable and wear-resisting in use, owing to the corrugated formation of the card tab and of its protecting and reinforcing sheath; it serves as a smooth and 45 convenient handle for tilting the card; and it is adapted to display a protected signal of large size at the proper angle of vision. When the signal appears upon a separate label or index slip, the label may be readily 50 inserted or removed from the sheath by hand, yet it will be effectively retained against casual displacement by contact with the correspondingly curved card tab and sheath flap between which it is frictionally held. It will be understood, however, that 55 the structural details herein described may be varied to suit particular purposes without departing from the essence of this invention as defined in the following claims.

60 I claim:

1. An index card having an integral projecting tab at one edge, said tab being transversely curved to form a corrugation extend-

ing substantially parallel to said card edge, a reinforcing sheath folded over the outer 65 edge of the tab and having front and rear flaps curved to correspond with the curvature of the card tab, and means for securing the sheath to the card with the sheath flaps overlying the surfaces of the tab, said front 70 flap being transparent to display signal means carried on the front face of the tab.

2. An index card comprising a body portion having an integral projecting tab at one edge, a reinforcing sheath folded over the outer edge of the tab and having front 75 and rear flaps, means for securing the inner corners of the front flap to the card, so that a label may be inserted behind said front flap between said securing means, the front 80 flap being transparent and said card tab and front flap being transversely curved, thereby frictionally to retain the label therebetween, and the rear flap extending downwardly over the rear face of the tab and being secured 85 to the card.

3. An index card comprising a body portion, a projecting tab at the upper edge of said body portion and integral therewith, a label holder of transparent sheet material 90 folded over the upper edge of said tab and having front and rear flaps extending downwardly beyond the upper edge of the body portion, means for holding the rear flap against the rear face of the card fastenings 95 at the lower corners of the front flap for securing the flap to the card body, and a removable label adapted to be inserted beneath the front flap and between the fastenings at the lower corners thereof, said front flap 100 and said card tab being transversely curved thereby frictionally to retain the label therebetween.

4. An index device comprising a card having an integral projecting tab at its upper edge, said tab being transversely curved to 105 form a corrugation extending substantially parallel to said card edge, a label receiving and reinforcing sheath of transparent sheet material folded over the upper edge of the card tab and having front and rear flaps curved to fit against the curved faces of the tab, fastenings for securing the lower corners of the flaps to the card, and a removable label adapted to be inserted upwardly 110 between said fastenings and frictionally retained beneath the front flap, with its upper edge reaching approximately to the upper edge of the tab and with its lower corners covered by said front flap, the central portion 115 of the lower margin of said flap being cut away to permit the label to be grasped for removal.

Signed by me at Boston, Massachusetts, this 7th day of June, 1928.

GEORGE H. DAWSON
